**EMBOSSED PLASTIC SHEET MATERIAL OR
SIMILAR ARTICLE**

**Paul Hirsch, New York, N.Y., assignor to Ropa
Industries, Inc., New York, N.Y.**

Filed July 3, 1972, Ser. No. 268,729

Term of patent 7 years

Int. Cl. D5—06

U.S. Cl. D87—3 G

The single figure of the drawing is a top plan view of a plastic sheet material showing my new design, the quatrefoil and the grill being embossed.

I claim:

The ornamental design for an embossed plastic sheet material or similar article, substantially as shown and described.
